WALL COVERING

Harold B. Little and Kenneth C. Miller, Baltimore, Md., assignors to The Baltimore Enamel & Novelty Co., Baltimore, Md.

Application June 23, 1932, Serial No. 618,993

4 Claims. (Cl. 189—86)

This invention relates to wall coverings, and particularly to enameled sheet metal wall coverings.

One object of the present invention is to provide a wall covering of this character which is so constructed that the different parts thereof may be easily and quickly assembled, on the wall, and as easily removed therefrom.

Another object is to provide a wall covering of this character wherein the joints of the different parts are properly concealed from view, and efficiently held against displacement.

Another object is to provide a wall covering of this character wherein the fastening means for the parts of the covering, and the joint covering means are concealed from view.

Other objects and advantages will be apparent from the following description when taken in connection with the accompanying drawings.

20 In the drawings:

Figure 1 is a fragmentary elevation of a wall covering, made in accordance with the present invention, which includes wall plates, a rail, and a base-board, with coverings for the joints thereof.

Figure 2 is a vertical sectional view on the line 2—2 of Figure 1.

Figure 3 is a vertical sectional view on the line 3—3 of Figure 2.

30 Figure 4 is a fragmentary elevation of a wall covering which covers the wall above the rail.

Figure 5 is a vertical sectional view on the line 5—5 of Figure 4.

Figure 6 is a horizontal sectional view on the line 6—6 of Figure 2.

Figure 7 is a perspective view of the upper end of the cover member 32.

Figure 8 is a horizontal sectional view through the corner of a room, showing the manner of covering the parts meeting therein.

Figure 9 is a view similar to Figure 8, showing another manner of covering the meeting parts in the corner of a room.

45 Figure 10 is a vertical sectional view, similar to Figure 2, showing the rail as an independent strip.

Figure 11 is a sectional view similar to Figure 5, showing the rail as an independent strip, in connection with the invention, when the wall is covered above the rail.

Figure 12 is an elevation similar to Figure 1, of the form of the invention illustrated in Figure 10.

50 Figure 13 is a fragmentary perspective view of

the independent rail and panel plate of the form of Figure 10.

Figure 14 is a fragmentary perspective view of the upper end of the panel plate of the form of Figures 1 and 2.

Referring to the accompanying drawings, and particularly to Figures 1, 2, and 3, 10 represents a number of rectangular, flat metal plates, which are disposed against the wall 11, with their vertical edges spaced apart. Driven into the wall, 65 midway between the said vertical edges of the plates, adjacent the upper and lower ends of said plates, are the screws 12, and engaged on each of the screws are the disks 13, 14, and 15, the former, which is of the greatest diameter, 70 is disposed against the faces of the plates, the next disk 14, being disposed outwardly of the first disk, while the disk 15, which is preferably cupped, is disposed outwardly of the disk 14.

The lower end of each of the sheets or plates 75 10 is curved outwardly and downwardly, at 16, and inwardly at 17, to rest on the floor 18, and form a base-board.

The upper end of each of the plates 10 is bent horizontally outward, as at 19, upwardly therefrom, as at 20, and thence horizontally inward, toward the wall, as at 21. The resultant of the bent portions 19, 20, and 21 form the rail, which extends completely around the room.

Disposed in covering relation to the vertical joints of the plates 10 are the covering members 22, each of which consists of an elongated strip of metal 23, the lower end of which is bent, as at 24, to conform with, and cover the outer portion of the lower end of each of the plates, at the sides of said joint, and rests on the floor. The body of each of these strips is spaced away from the plane of the plates 10, and has its side edges bent inwardly, as at 25, to engage against the faces of the adjacent plates 10. These edges are finally doubled on themselves, as at 26. Properly secured to the inner face of the body of each of the said covering strips are the offset tongues 27, the lower ends of which are cut away, as at 28, whereby to produce the spaced leg portions 29, which engage between the cupped disk 13 and the disk 14, in straddling relation to the smaller disk 14, whereby to hold said strip in proper position to cover the joint between the adjacent plates 10.

Disposed in covering relation to the joint between the rail sections is a cap member 30, the inturned side portions 31, of which, extend inwardly and contact with the adjacent portions of the outer faces of the rail ends. The cap is 105 110

formed with a downwardly extending angular portion 32, which embraces the upper end portion of the covering strip 22.

Secured to the inner face of the cap 30 is a substantially U-shaped member 33, the legs of which bear against the wall. The transverse portion of the member 33 is provided with an opening 34, registering with a similar opening 35, in the center of the cap, to receive the screw 36, which is driven into the wall, for holding the parts together, and in proper position on the wall.

When the wall is covered with plates 10, above the rail, the joints between the plates are covered by the strips 23', and the upper side of each cap 30 is provided with an upwardly extending angular portion 32', which embraces the upper portion of said strip, as clearly seen in Figures 4 and 5, of the drawings.

It will be particularly noted, from an inspection of Figures 4 and 5, that the lower edge of the upper panel plate is bent, in a manner identical with that of the upper edge of the plate, which is used below the rail, and that in this instance the upper edge of the lower panel plate is unformed, and extends upwardly behind the lower portion of the rail. This is clearly seen in Figure 5.

In some instances it may be more desirable or convenient to use independent rails, instead of forming the rails on the panel plates. This is illustrated in Figures 10, 11, 12, and 13, of the drawings.

As clearly seen in Figure 10, the panel plate 10'' is disposed against the wall, and against the upper portion of its outer face is engaged the lower inturned portion of the rail 42, the inturned upper portion of the rail being engaged against the wall. A cap or cover 30'' embraces the meeting ends of the two rail sections 41 and 42, said cap having the downwardly extending channeled portion 32'', which embraces the upper end of the cover member 22'', of the joint of the panel plates. The cap 30'' is secured in place by the screw 36'', and to prevent inward bending of the cap, when the screw is tightened, an angular U-shaped spacing and bracing member 33'' is interposed between the cap and the wall, and lying between the adjacent ends of the two rail sections 41 and 42, the screw passing through an opening in the intermediate transverse portion of said member.

When panel plates are used above the rail, the cap is provided with an extension 32'' projecting above the rail, as clearly seen in Figure 11, of the drawings, said extension embracing the lower end of the plate joint cover strip 23''. The construction and arrangement of the parts, in this instance being practically the same as when the plates are used below the rail.

The construction of the upper edge of a panel plate, used below the rail, is clearly shown at 20, in Figure 14.

When a corner of a room is reached, a plate 10' is bent at right angles, to fit in the corner, as at 37 in Figure 8, of the drawings, the side edges of said plate, on the adjacent walls, being held, with relation to the adjacent panel plates 10, of said walls, by the disks 13, and 15, and the tongues 40, carried by the angularly bent cover plate 39.

Another manner of treating the wall covering, in the corner of a room is shown in Figure 9, wherein a comparatively large angle plate 38 is used to fit into the corner. The side edges of this angle plate 38, together with the adjacent vertical edges of the wall or panel plates 10, are covered by the strips 22, held in place by the disks 13 and 15, and the tongues 40', the latter carried by said cover strips.

What is claimed is:

1. A wall covering comprising plates each having rail and base-board portions, means for attaching the plates to a wall comprising a screw and disks thereon, a covering strip for the joint between adjacent plates, a tongue on said strip engaged between said disks, and a cap covering the joint between adjacent rail portions having an extension embracing a portion of said strip.

2. A wall covering comprising plates arranged with their vertical edges in spaced relation, a fastening means including a screw passing between said edges and engaged in a wall, disks on the screw, a spacing disk between said disks, and a covering strip for the joint between the adjacent plates, and a tongue on the covering strip engaging the spacing disk between the spaced disks.

3. In combination, a pair of spaced wall plates, a channel-like cover member straddling the space between said plates, securing means including spaced flange portions, means to secure said securing means to a wall behind the channel member, and a clip fixed to the under side of the channel member and having a rearwardly offset lower end engaged between the said spaced flange portions.

4. In combination, a pair of spaced wall plates, a channel-like cover member straddling the space between said plates, a securing member including spaced portions, means to secure said securing member to a wall behind the channel member, and a clip fixed to the under side of the channel member and having a rearwardly offset lower end engaged between said spaced portions, one of said spaced portions being of such width as to span and rest on the adjacent edges of the wall plates.

HAROLD B. LITTLE.

KENNETH C. MILLER.
